United States Patent Office.

JAMES B. CLARK AND LUCAS C. CLARK, OF PLANTSVILLE, CONNECTICUT.

Letters Patent No. 97,762, dated December 14, 1869.

IMPROVEMENT IN MACHINES FOR BENDING AND FOLDING SHEET-METAL.

The Schedule referred to in these Letters Patent and making part of the same.

To all whom it may concern:

Be it known that we, JAMES B. CLARK and LUCAS C. CLARK, of Plantsville, in the county of Hartford, and State of Connecticut, have invented new and useful Improvements in Machine for Bending or Folding Sheet-Metal; and we do hereby declare that the following is a full, clear, and exact description thereof, reference being had to the accompanying drawings, making part of this specification, in which—

Figure 1 is a front elevation of our invention.

Figure 2 is a side elevation of the same.

Figure 3 is a close sheet-metal lock.

Figure 4 is an open sheet-metal lock.

Similar letters of reference indicate like parts.

Our invention consists in the use or employment of two swinging brakes, in combination with a folding-plate, and also in the arrangement of a part of the upper brake, so that it receives a circular and vertical motion in turning an open lock.

A designates the bed or frame of the machine, to which is firmly secured a folding-plate, B.

Underneath the folding-plate B is a swinging brake, C, which is fitted to swing in bearings, the position of which bearings is indicated by the broken circle in fig. 2.

Immediately back of the brake C is a brake, D, which is pivoted to swing in bearings, E.

The upper end of the brake, D is pivoted at each end to a cam, F, which cams are connected to each other by a bar, G, to which is attached the lever H.

The bed A is provided with an arm, I, on the end of which is a roller, a, which fits into a corresponding depression in the cams F.

On the front side of the brake D is a sliding plate, J, which is secured to the same by screws c c, running through the slots d d.

When desired to turn a close lock, the plate J is brought down and secured rigidly in place by the pin i.

The metal plate K is inserted with one edge against the shoulder m, on the brake C, as shown in fig. 2. The cams F, by means of the lever H, are turned forward or toward the folding-plate B, which causes the brakes D and C to move simultaneously, one under and one over the edge of the folding-plate B, and thus form or swage the metal K closely to the plate B, into the form shown in fig. 3.

To turn an open lock, fig. 4, the pin i is removed, which allows the springs, back side of the brake D, indicated by broken lines n, to raise the plate J until the screws c c strike the upper ends of the slots d d. As the brakes D and C are brought forward, the plate J strikes the metal K above the folding-plate B so far as to allow the metal to assume a rounding form, and when the brakes are nearly as far forward as the cams F will throw them, a portion of the cams F strike the projections o, on each end of plate J, and throw it downward toward the folding-plate B, until the lock is formed as close as may be desired.

When the plate J is raised for the purpose of turning open locks, it cannot be made to move forward far enough to form the metal as close to the folding-plate B as is desired, without the vertical movement of the same, substantially as described.

What we claim as new, and desire to secure by Letters Patent, is—

1. The combination of the swinging brakes C and D, and the folding-plate B, substantially as and for the purpose described.

2. The combination of the swinging brakes C and D, folding-plate B, brake-plate J, and cams F, all constructed and operated substantially as set forth.

JAMES B. CLARK.

LUCAS C. CLARK.
